DESIGN FOR A BELL TOY

Eunice New, formerly Dennice New,
South Jacksonville, Fla.

Application July 24, 1945, Serial No. 120,921

Term of patent 14 years

(Cl. D34—15)

To all whom it may concern:

Be it known that I, Eunice New, formerly Dennice New, a citizen of the United States, residing at 2123 Hendricks Avenue, South Jacksonville, in the county of Duval and State of Florida, have invented a new, original, and ornamental Design for a Bell Toy, of which the following is a specification, reference being had to the accompanying drawing, forming part thereof.

I claim:

The ornamental design for a bell toy, as shown.

EUNICE NEW,
Formerly Dennice New.
